UNITED STATES PATENT OFFICE.

HARRY F. ROACH, OF ST. LOUIS, MISSOURI.

INSULATED RAIL-JOINT.

1,258,253.

Specification of Letters Patent.

Patented Mar. 5, 1918.

Application filed August 6, 1917. Serial No. 184,654.

To all whom it may concern:

Be it known that I, HARRY F. ROACH, a citizen of the United States, residing at St. Louis, Missouri, have invented a certain new and useful Improvement in Insulated Rail-Joints, of which the following is a full, clear, and exact description, such as will enable others skilled in the art to which it appertains to make and use the same.

10 This invention relates to insulated rail joints of the so-called "splice type," namely, joints in which splice members consisting of fish plates or angle bars are arranged on opposite sides of the webs of the rails in engagement with insulating members that bear against the base flanges and the heads of the rails.

One object of my present invention is to provide an insulated rail joint of the general type referred to, which is so constructed that the wave motion of the rails throughout the track is continued uniformly through the joints of the track, thereby eliminating "hard spots" in the track, and consequently, 25 reducing the liability of the rails to break within the joints or at the ends of the joints, as so often occurs in insulated splice type rail joints of the kind now in general use, due to the fact that the side members of such 30 joints are so designed that they impart considerable additional stiffness to the portions of the rails which they embrace.

Another object of my invention is to provide an insulated splice type rail joint which 35 is so designed that it minimizes the vertical bending moment at the center portion of the joint to a negligible degree and causes the center portion of the joint to be brought into structural shear resistance.

40 Another object is to provide an insulated rail joint of the general type referred to which is so constructed that it overcomes the necessity of accurately spacing the track ties.

Another object is to provide a splice type 45 insulated rail joint which insures the wave motion of the rails being continued uniformly through the joints of the track without liability of the insulating material at the sides of the rails being cut by the movement of the rails relatively to the side members of the joint when the rails are under load.

And still another object of my invention 50 is to provide an insulated rail joint in which the end post between the ends of the abutting rails can be removed or replaced with-

out the necessity of removing the bolts and the side insulating members, as is necessary in insulated rail joints of the kind now in general use. Other objects and desirable features of my invention will be hereinafter 60 pointed out.

To this end I have devised an insulated rail joint which comprises side members arranged on opposite sides of the webs of the 65 abutting rails, insulating members interposed between said side members and the heads, webs and base flanges of the rails, and an end post arranged between the ends of the rails, said side members being provided intermediate their ends with portions 70 that are wedged tightly between the heads and the base flanges of the rails in proximity to the center of the joint, and the ends of said side members being so constructed and 75 arranged that they are spaced away from the heads and the base flanges of the rails sufficiently to permit the rails to move vertically at the ends of the joint under load both upwardly and downwardly. The joint 80 can either be positioned over a tie or between two ties, and the side members of the joint may be of any preferred shape in cross section and can either be cast, rolled, forged or formed by a combined rolling, bending or 85 shaping operation. The bolts of the joint are insulated from the side members and from the rails by suitable insulating devices, and the end post can be of any suitable design. I prefer, however, to use an end post 90 which is constructed in such a manner that it can be removed and replaced without removing the bolts and the side insulating members, and so far as this feature of my invention is concerned, it is immaterial how 95 the side members of the joint are constructed, or whether the joint is of the so-called splice type or of the type in which the rails are supported by a base plate.

Figure 1 of the drawings is a side elevational view of an insulated rail joint constructed in accordance with my invention.

Fig. 2 is a horizontal longitudinal sectional view of the same.

Fig. 3 is a view partly in end elevation 105 and partly in vertical section, taken on the line 3-3 of Fig. 1.

Fig. 4 is a perspective view of the end post.

Fig. 5 is a side elevational view, illustrating a slight modification of my invention.

Fig. 6 is a horizontal longitudinal sec-

tional view of the joint shown in Fig. 5; and

Fig. 7 is a perspective view of one of the metallic fillers used in the joint shown in 5 Fig. 5.

Referring to Fig. 1 of the drawings, which illustrates the preferred form of my invention, A designates two members that are arranged on opposite sides of the vertical webs of two abutting rails B, and C and C' designate bolts or other suitable fastening devices that pass transversely through said side members A and through the webs of the rails. Insulating members D are arranged between the rails and the side members A, and an end post E formed of suitable insulating material is interposed between the ends of the rails B. The bows of the joint are insulated from the side members A by insulating devices F of conventional form. Each of the side members A is provided intermediate its ends with means 1 and 2 that are wedged between the undersides of the heads 3 of the rails and the upper sides of the base flanges 4 of the rails, respectively, in proximity to the center of the joint, said means 1 and 2 preferably consisting of integral portions on the upper and lower edges of each of the side members 10 A that extend a short distance on each side of the end post E between the ends of the rails. The end portions of each of the members A are spaced away from the heads and from the base flanges of the rails, or rather, 15 from the portions of the side insulating members D that contact with the heads and base flanges of the rails, so as to permit the rails B to deflect slightly and also move upwardly at the ends of the joint under 20 load. By constructing the side members A of the joint in this manner I obtain practically a hinge connection between the terminals of the rails and the center portion of the joint without the use of a base plate or 25 supporting structure under the base flanges of the rails. When the joint is in service the load imposed on one rail by a wheel traveling over the same will be transmitted to the center portion of the joint through 30 the end of the rail, thus bringing the members A into shear resistance at the center of the joint. When the load passes from said rail onto the adjacent rail the load will be transmitted through the end portion of the latter to the center portions of the members A in exactly the same manner as just described. It will thus be seen that in an insulated rail joint of the construction herein 35 illustrated the vertical bending moment of the side members A at the center of the joint is reduced to a negligible degree so that it is not necessary to consider the bending moment as a factor in designing the joint for the particular work that it is required to do. The hinge connection between 40 the rails and the side members A of the joint eliminates hard spots in the track and prevents reverse strains from being created in the joint, as such a connection permits the wave motion of the rails to pass through 45 the joint uninterrupted. Furthermore, such an insulated joint can be made as stiff as desired without causing the rails to break, owing to the fact that it does not add materially to the stiffness of the portions of the rail which are embraced by the side members A. My improved joint is not only superior to insulated splice type rail joints in the respects previously pointed out, but it can be made much lighter without affecting 50 the efficiency or sacrificing strength, on account of the fact that the joint members A are of such design that the center portions of the same are subjected to vertical shearing strains, instead of vertical bending strains 55 when the joint is in service. The length or area of the portions 1 and 2 of the members A can be varied, so long as the end portions of said members are spaced far enough away from the undersides of the heads of the rails and from the upper sides of the base flanges of the rails to permit the rails to move vertically at the ends of the joint upwardly and downwardly under load. As previously 60 stated, the members A may be of any preferred cross-sectional shape and may be formed in various ways without departing from the spirit of my invention. 65 The joint herein illustrated is so designed that when it is in service the portions 1 and 2 of the side members A will bear with greater force against the side insulating members D at points in proximity to the center bolts C than they do at the points where the terminals of the rails contact 70 with said side insulating members D. The purpose of constructing the joint in this manner is to provide sufficient relief for the side insulating members D at the center of the joint to prevent said insulating members from being cut or damaged by the terminals of the rails, due to the up and down movement of the rails under load and also to further reduce the stiffness of the portions of the rails which are embraced by the 75 side members A of the joint. I accomplish this by designing the side members A in such a manner that when they are installed the end bolts C of the joint can be drawn up tight enough to force the end 80 portions of the side members A inwardly toward the vertical webs of the rails, and thus bow out the center portions of the side members A at the center of the joint, as shown in Fig. 2. The result is that when 85 the joint is in service the rails will be practically hinged to the side members A of the joint at points in proximity to the center bolts C of the joint, instead of throughout 90 the entire length of the portions 1 and 2 of 95

the members A that are wedged between the heads and the base flanges of the rails. By the above statement I do not wish to intimate that the side members A of the joint 5 do not bear against the side insulating members D at points between the center bolts C, for in practice the intermediate portions of the members A are wedged between the heads and base flanges of the rails 10 at the center of the joint. The degree of pressure, however, that the members A exert on the side insulating members D at the exact center of the joint, or, in other words, at the terminals of the rails B, is less 15 than the degree of pressure which the members A exert on the side insulating members D at points in proximity to the center bolts C, due to the bowing out of the intermediate portions of the side members A when 20 the end portions of the members A are drawn inwardly by tightening the end bolts C'. It is not absolutely essential that the side members A of the joint be installed in this manner, for if desired, said side 25 members can be so arranged that they will extend parallel to the webs of the rails, thus causing the intermediate portions 1 and 2 of said members to exert the same pressure throughout their entire length on the portions 30 of the insulating members D that are interposed between the same and the heads and base flanges of the rails, but as previously stated, it is preferable to arrange the side members A of the joint in such a manner 35 that a slight relief is provided for the side insulating members D at the center of the joint, as I have found that this tends to prevent the terminals of the rails from cutting the side insulating members D and it 40 also tends to reduce the stiffness of the portions of the rails that are embraced by the joint.

The end post E, instead of being provided with a base portion that is interposed between the base flanges of the rails, as has heretofore been the usual practice, merely 45 consists of a member formed of suitable insulating material and provided with a head portion 5 that lies between the heads of the rails and a shank portion 6 that lies between the vertical webs of the rails. When it becomes necessary to replace the end post E of the joint, this can be accomplished by 50 simply loosening the bolts of the joint and drawing the end post E upwardly from between the ends of the rails. A new end post can then be installed by simply inserting or arranging the shank portion 6 of the same 55 between the ends of the rails and forcing 60 said end post downwardly into operative position. So far as this feature of my invention is concerned, it is immaterial how the side members of the joint are constructed.

55 In the form of my invention illustrated

in Fig. 1 the side insulating members D extend throughout the entire length of the side members A of the joint, but this is not necessary, for if desired, the side members of the joint could be insulated from the rails by 60 said insulating members that extend inwardly from the ends of the joint to points a slight distance past the end post, and metal fillers could be arranged between the remaining portions of said side insulators and the 65 rails. Such a construction is not only desirable in that it reduces the quantity of insulating material used in the joint, but it also tends to prolong the life of the insulating material by providing metal bearing 70 surfaces for the terminal portions of the rails to act upon when the joint is in service. In Figs. 5 to 7 of the drawings I have illustrated an insulated rail joint constructed in this manner that is intended to be used on 75 a single track, namely, a track on which the traffic travels in both directions. The side members A of the joint shown in Fig. 5 are of the same construction as those used in the joint illustrated in Fig. 1, but the side insulating members D' terminate at points in 80 proximity to the center of the joint, instead of extending throughout the entire length of the joint. As shown in Fig. 6, the side insulating member D' that is arranged at 85 one side of the rails extends inwardly from one end of the joint to a point a short distance beyond the end post E, and the other side insulating member D' that is arranged at the opposite side of the rails extends in- 90wardly from the opposite end of the joint to a point a slight distance beyond the end post E. Two metal fillers G are arranged at opposite sides of the rails, as shown in 95 Fig. 6, so as to form continuations of the side insulating members D', each of said metal fillers G being provided with a sub- 100stantially channel-shaped portion 7 that conforms to the cross-sectional shape of the inner end portion of the insulating member 105 D' with which it cooperates and a horizontally-disposed, straight, web portion 8 through which one of the center bolts and one of the end bolts of the joint pass. When 110 such a joint is in service the metal fillers G serve as metal bearing surfaces on which the terminal portions of the rails act when the rails are under load, and as said metal fillers have greater wear resisting properties than the insulating members D', they prolong the 115 life of said insulating members. Furthermore, as said metal fillers are clamped between the heads and the base flanges of the rails and have openings through which the 120 bolts of the joint pass, it will be impossible for said metal fillers to work loose or become displaced. I prefer to form the metal fillers G in the manner illustrated in Figure 125 7, but the particular shape or form of said metal fillers is immaterial so far as my broad 130

idea is concerned, so long as they are of such form that they comprise portions that form continuations of the parts on the side insulating members D' that coöperate with 5 the means 1 and 2 on the side members A to form fulcrums for the terminal portions of the rails, it being essential, however, that the outer end portions of the metal fillers G be of such design that they will not interfere 10 with the vertical movements of the rails when the rails are under load.

When an insulated rail joint of the general character illustrated in Figs. 5 to 7, inclusive, is used for double track work, namely, 15 in a track on which the traffic travels in only one direction, the metal fillers G are arranged on opposite sides of the receiving rail and the insulating members D' are arranged on opposite sides of the delivering rail, so 20 that the portions of the metal fillers that lie between the upper and lower edges of the side members A and the heads and base flanges of the rails will receive most of the impact produced by a wheel passing over 25 the joint.

Having thus described my invention, what I claim, and desire to secure by Letters Patent, is:

1. An insulated rail joint, comprising 30 side members arranged on opposite sides of the rails and having their end portions spaced away from the heads and from the base flanges of the rails, means arranged intermediate the ends of each of said members that forms bearing surfaces for the heads and base flanges of the rails, and insulating material interposed between the rails and said side members.

2. An insulated rail joint, comprising 40 coöperating members spaced apart to receive abutting rails and provided with means lying in different horizontal planes than the end portions of said members to form bearing surfaces for the undersides of the heads 45 and the upper sides of the base flanges of the rails, and insulating material interposed between said members and the rails which they embrace.

3. An insulated rail joint, comprising 50 two members arranged on opposite sides of the webs of the rails and provided intermediate their ends with means that coöperates with the heads and with the base flanges of the rails to form substantially hinge connections 55 between the rails and the center portion of the joint, said members being so constructed and combined with the rails that the rails can move vertically, both up and down relatively to said members at the ends of the 60 joint when said rails are under load, and means for insulating said members from the rails which they embrace.

4. An insulated rail joint, comprising 65 side members arranged on opposite sides of the webs of the rails, and insulating material

interposed between said members and the rails which they embrace, said side members being so constructed and combined with the rails that the rails can move vertically, both up and down relatively to said members 70 sufficiently at the ends of the joint when the rails are under load to permit the wave motion of the rails to pass through the joint.

5. An insulated rail joint, comprising two 75 members arranged on opposite sides of the webs of the rails, and insulating material interposed between said members and the rails, the end portions of said members being spaced away from the heads and the base flanges of the rails and the intermediate 80 portions of said members bearing against parts of said insulating material that contact with the heads and with the base flanges of the rails.

6. An insulated rail joint, comprising two 85 members arranged on opposite sides of the webs of abutting rails above the base flanges of the same and designed in such a manner that they support and connect the terminals 90 of the rails together, but still permit the rails to move vertically, both up and down, relatively to said members at the ends of the joint when the rails are under load, and insulating material interposed between said 95 members and the rails.

7. An insulated rail joint, comprising two 100 members arranged on opposite sides of the webs of abutting rails and provided with intermediate portions lying above the base flanges of the rails on which the terminal portions only of the rails bear, thereby permitting the rails to fulcrum on said intermediate portions and move vertically, both up and down, at the ends of the joint when 105 said rails are under load, and means for insulating said members from the rails which they embrace.

8. An insulated rail joint, comprising 110 members arranged on opposite sides of the webs of abutting rails and having intermediate portions that are wedged between the heads and the base flanges of the rails, the length of said intermediate portions being less than the distance between the end bolts of the joint, so as to permit the rails 115 to move vertically, both up and down, relatively to said members at the ends of the joint when the rails are under load, and means for insulating said members from the rails.

9. An insulated rail joint, comprising 120 side members arranged on opposite sides of the webs of abutting rails, and insulating elements arranged between said members and the rails, said members being provided intermediate their ends with portions that co-operate with the heads and with the base flanges of the rails to form practically hinge 125 connections between the rails and the center portions of said members, thereby permit- 130

ting the rails to move vertically, both up and down, relatively to said members at the ends of the joint when the rails are under load.*

- 5 10. An insulated rail joint, comprising side members arranged on opposite sides of the webs of the rails with their end portions spaced away from the heads and the base flanges of the rails, and insulating elements 70
10 that are wedged against the undersides of the heads and the upper sides of the base flanges of the rails at the center of the joint by the intermediate portions of said side members.
- 15 11. An insulated rail joint, comprising side members arranged on opposite sides of the rails with their end portions spaced away from the heads and the base flanges of the rails, and insulating elements interposed 75
20 between said side members and the rails, said side members being provided intermediate their ends with means that coöperate with the heads and with the base flanges of the rails to form fulcrum points for the rails 80
25 located at each side of the exact center of the joint.
12. An insulated rail joint, comprising side members arranged on opposite sides of the webs of abutting rails with their end 85
30 portions spaced away from the heads and the base flanges of the rails, and insulated elements interposed between said rails and side members, said side members being provided with intermediate portions that form 90
35 fulcrum points for the heads and the base flanges of the rails and being so disposed that a slight relief is provided for the portions of said insulating elements on which the terminals of the rails act.
- 40 13. An insulated rail joint, comprising side members arranged on opposite sides of the webs of abutting rails and provided with end portions that are spaced away from the heads and the base flanges of the rails, and 95
45 insulating elements arranged between said members and rails, said side members being provided intermediate their ends with portions that are wedged tightly between the 100
50 heads and the base flanges of the rails in proximity to the center bolts of the joint.
14. An insulated rail joint, comprising side members arranged on opposite sides of the webs of abutting rails and having their end portions spaced away from the under- 105
55 sides of the heads and the upper sides of the base flanges of the rails, insulating elements interposed between the side members of the rails, and intermediate portions on 110
60 said side members that coöperate with the heads and the base flanges of the rails to form practically hinge connections between the rails and said side members at points a slight distance to either side of the exact center of the joint, said side members being 115
65 so disposed that a slight relief is provided for the insulating elements between the fulcrum points on said sides members.
15. An insulated rail joint, comprising side members arranged on opposite sides of the webs of abutting rails with their end 70
75 portions spaced away from the heads and the base flanges of the rails and their intermediate portions wedged between the heads and the base flanges of the rails, the end portions of said members being drawn inwardly toward the webs of the rails so as to cause the center portions of said members to bow out slightly, and insulating elements interposed between said elements and the rails.
16. An insulated rail joint, comprising side members arranged on opposite sides of the rails, insulating elements arranged between said side members and the rails, and an end post of insulating material interposed between the ends of the rails and 85
80 constructed in such a manner that it can be removed or replaced without removing said insulating elements.
17. An insulated rail joint, comprising side members arranged on opposite sides of the rails, insulating elements arranged between said side members and the rails, and an end post of insulating material interposed between the ends of the rails and 90
95 comprising a head portion and a depending shank portion of such form that it can be removed or replaced without removing the insulating elements between said side members and rails.
18. An insulated rail joint, comprising side members arranged on opposite sides of the web of abutting rails with their end portions spaced away from the heads and the base flanges of the rails, means intermediate the ends of said side members that coöperate with the heads and the base flanges of the rails to form fulcrum points for the rails when the rails are under load, and insulating elements and metal fillers interposed between the rails and the intermediate portions of said side members on 100
105 which the rails fulcrum.
19. An insulated rail joint, comprising side members arranged on opposite sides of the webs of abutting rails and provided with end portions that are spaced away from the heads and the base flanges of the rails and intermediate portions that are wedged between the heads and the base 110
115 flanges of the rails, insulating elements arranged between said side members and rails and extending across the space between the ends of the rails, and metal fillers that form continuations of said insulating elements 120
125 and provided with portions through which the bolts of the joint pass.
20. An insulated rail joint, comprising side members arranged on opposite sides of the rails and provided intermediate their 130

ends with portions that coöperate with the heads and the base flanges of the rails to form substantially hinge connections between the rails and said side members, the 5 end portions of said side members being spaced away from the heads and the base flanges of the rails, insulating elements arranged on opposite sides of the rails between the rails and said side members and extending 10 inwardly from opposite ends of the joint, and metal fillers that form continuations of said insulating elements and provided with portions that are interposed between said side members and the heads and 15 base flanges of the rails.

21. An end post for insulated rail joints, consisting of a member formed of insulat-

ing material and provided with a head portion and a depending shank portion of such shape and design that the end post 20 can be removed or replaced without removing the bolts or the side insulating elements of the joint.

22. An end post for insulated rail joints, consisting of a member formed of insulating material and provided with a head portion and a depending shank portion 25 whose lower end is of less width than said head portion, thereby permitting the end post to be removed or replaced without removing the bolts or the side insulating elements of the joint.

HARRY F. ROACH.
